Application August 23, 1938, Serial No. 226,370
 In Germany August 26, 1937

2 Claims. (Cl. 235—130)

This invention relates to printing calculating machines and has for its object a safety device for preventing unauthorized interference or meddling with the machines and more particularly every unauthorized use or disarrangement of the machine by any unauthorized person and against an unauthorized change of the setting by the operator. It is therefore an object of this invention to provide a lock mechanism to lock the frame carrying control members to prevent an unauthorized setting or changing of the machine.

In accordance with the invention a lock is provided for this purpose the closing of which shuts off or arrests all the means which are actuated by the digit keys and sign keys as well as arresting the transversely slidable carriage. The arresting may be limited thereto that the said means, that is the calculating and printing mechanisms of the machine cannot be actuated, but that the keys themselves may be pressed down without however having any influence on the other elements otherwise actuated thereby, and said keys automatically returning to their position of rest.

It is furthermore advantageous, when driving the machine by an electric motor, to provide a special switch for the motor in the feed circuit, which switch is opened by closing the lock in accordance with the present invention. Although the motor generally is not switched on but in the case calculating and printing mechanisms are brought into action, it may however be desired to switch it off independently thereof in order to prevent the motor from being started, by unauthorized interference of any kind.

Furthermore, a latch or arrester is suitably provided for the keys of the total taking mechanism or for the elements actuated thereby and preferably by means of a special lock therefor, whereby there will be presented the possibility of preventing the operator to take totals.

Finally in order to prevent any unauthorized change in the setting of the paper carriage control of the machine either by the operator or any other person, a machine having a "rider", such as for instance a frame carrying control tappets and being secured on the paper carriage, may be provided with a latch for locking the means which secure the frame on the paper carriage, which latch may suitably be constructed so that it can only be released at an end position of the carriage. The carriage practically never stays in this end position, when the machine is not used, because in the end position of the carriage the protecting hood cannot be placed over the ma-

chine. In accordance with this invention any release of the frame carrying the control tappets for changing the adjustment of the tappets is therefore prevented when the machine is locked, because the carriage is arrested, that is, it cannot be brought into that end position wherein the carrying frame can be released for changing the position of any tappets. But even during the working of the machine, any such change of the tappet positions can be prevented, when there is a possibility of release of the carrying frame in the carriage end position by operating the said latch by means of a special key-operated lock provided therefor.

15 Of the last named devices, that is the locking latch for the keys of the total taking mechanism and that for the arresting of the carrying frame, may also be arranged the one alone.

The drawings illustrate diagrammatically the 20 invention and show in Fig. 1 a calculating machine in plan view partly in section.

Fig. 2 a side view in the direction of the arrow A of Fig. 1 and partly in section,

Fig. 3 a side view in the direction of the arrow B of Fig. 1 and partly in section,

Fig. 4 a side view also in the direction of arrow B of Fig. 1 partly in section along line IV of said figure, and

Fig. 5 a section taken on line V—V of Fig. 1.

30 Upon the main frame or casing 1 of the calculating machine there is arranged on one side a lock 2, Fig. 1, the crank-like member 3 of which carries a pivot pin 4, Fig. 4, upon which the rod 5 is pivoted and which also engages the slide 6 horizontally movable in a long slot provided in the stand 1. The member 3 is fastened to the shaft 2' of the lock 2. The rotation of the member 3 in both directions is limited by a pin 3' which is provided on the machine frame 1. The

35 other end of the rod 5 as shown in Fig. 4 grips the pin 7 of the lever 8, which latter is mounted on the shaft 9 mounted in bearings in the main frame 1. This shaft also carries a second lever 10 connected with the rocker 13 turning on a pivot 12 in the main frame 1, by means of the rod 11 which is parallel to the key surfaces. Motor keys 15, each provided with a side nose 14, are arranged in the casing 1. On pins 16 are suspended the latches 17, which together with

40 the rocker 13 form an arresting chain between the members of which, at any one time only a single one of the noses 14 can be situated, so that also only one of the motor keys 15 can be depressed in coupling position.

45 In the casing 1 at the side of the shaft 9 a shaft

18 is revolvably mounted. A lever 19 is mounted on shaft 18 and having a pin 20 engaging in a longitudinal slot in the rod 21 which is linked to the pin 7 of the lever 8.

On shaft 18 are provided levers 22, one for each order of the amount keys 23 and for the row of sign keys 24. In each lever 22 there is a slot in which the pin 25 engages. There is a pin 25 on each releasing rail 26, which latter is arranged slidably under the key surfaces in the main frame 1 and which is actuated by a spring 27. Each rail 26 possesses a plurality of hooked noses 29, for holding down the keys 23 and 24 which are depressed against the force of the springs 28.

A lever 30 on shaft 18 is provided at right angle to the levers 22 and this lever 30 is provided with a longitudinal slot, into which the pin 32 projects which is fastened on the releasing key 31. The shaft 18 also carries the lever 33 as shown in Fig. 2 which lever can be rotated in clockwise direction for locking the arm 34, this arm being pivoted on pin 35 in the casing 1 at a distance below the total key 36 for taking the totals from the accumulators. The arm 34 may also be locked by the rotatable member 37 of a lock 38, this lock being positioned on the side wall of the casing 1.

The slide 6 engages a lever 39 which is rotatably mounted on the bottom of casing 1, and the other end of the lever is engaged by the rod 40 which transfers its movement to the vertically slideable shaft 42 through the intermediary of a bell crank 41 as shown in Fig. 3. The shaft or rod 42 acts from below on the lever member 44, which is under influence of the tension spring 43, Fig. 5, and one arm of which carries internal teeth situated opposite the gear wheel 45 for driving the carriage.

To the slide 6 there is also linked the push rod 46 which acts with its stud 47 of insulating material on the control spring 48 pushing against the contact 49. This contact breaker formed by these two contacting members may serve for disconnecting the feed current for the driving motor of the machine.

In the carriage 51, Fig. 5, is mounted on bearing points or pins 52, 53 a box-like frame 50, which may serve for reception of members for controlling the paper carriage column positions and various functions of the machine. Such members are for instance shown in French Patent No. 795,028 and in the corresponding U. S. application Serial No. 39,065, filed September 3, 1935. This patent shows control tappets and control members in a frame which is removably secured on the paper carriage as shown in Figs. 14 to 16. The bearing point 53 is threaded into the carriage and can accordingly be axially adjusted by means of the hand wheel 54. Unscrewing the pin will permit the lifting out of the frame 50 from the carriage 51 for example for changing the positions of control members.

Upon the bearing pin 53 there is secured the gear wheel 56 under the hood or casing 55. Within the hood a two armed lever 58 is mounted to turn on the pivot 57, said lever 58 carrying a tooth 59 opposite the gear wheel 56 and is bifurcated at its end, Fig. 2. The crank-like member 60 engages the bifurcated arm of the lever 58 by means of a pin 61, said member being part of the lock 62 provided on the casing 55. The other end of the lever 58 is arrested by the angular latch 63 pivoted on the pin 64 in the carriage 51. When the carriage 51 arrives in its right hand end position, then the angular latch 63

63, while tensioning the spring 65, is turned by the lug 66 arranged in the main frame 1, thus setting the lever 58 free, so that the tooth 59 can be disengaged from the gear wheel 56 by operating the lock 62. The bearing point 53 may now be screwed out far enough to permit the removal of the frame 50 from the carriage.

If after the use of the machine the lock 2 is operated, then the member 3 turns upwards counter-clockwise from the working position of the machine shown in Figs. 3 and 4. It then pushes the slide 6 towards the right, so that the contact spring 48 is lifted from the corresponding contact 49 thereby breaking the motor circuit. By the displacement of the slide 6 the lever 39 is turned and the rod 40 drawn forwardly in the machine whereby the shaft 42 drops by its own weight. The lever member 44 can now be turned by the spring 43 thereby placing its toothed arc in mesh with the gear wheel 45 thus arresting the same, so that consequently no movement of the carriage is possible. Furthermore, the member 3 has also displaced the rods or links 5 and 21, Fig. 4, and thereby rotated the shafts 9 and 18 counter-clockwise. The shaft 9 thus drives the rod 11 forward in the machine and has also turned the rocker 13 on its pivot, whereby the latter becomes pressed against the arresting latch 17, so that the row of arresters or latches is now closed and thus no motor key can be depressed. By shaft 18 the rails 26 are also moved forward in the machine through the intermediary of lever 22, Fig. 3. Should then one of the amount keys 23 be touched, it cannot produce any displacement of the rail 26, but does also not engage below the corresponding hooked nose 29 of the rail 26, and will not accordingly be held depressed, but will instead immediately jump up, as soon as released. No positioning of the rails 26 is thus possible, their moving moreover being stopped on account of the non-rotation of the motor.

With the turning of the shaft 18 the lever 33 is turned clockwise upwards, Fig. 2, which shows the other side of the machine. Thus it will grip under the arm 34 and hold it stationary, so that the total key cannot be depressed any more.

After the use of the machine the carriage is generally placed in the middle position. The angular latch 63, actuated by the spring 65, then lies in the path of the lever 58. The same cannot therefore be brought into the position to set the gear wheel 56 free by the opening the lock 62, so that any unscrewing of the bearing points 53 and consequent removal of the frame 50 is made impossible. The latter can, therefore, only be taken out when the lock is open, but the lock can only be opened with the carriage in end position but on the contrary however, it can be closed with the carriage in any position.

Advantageously the construction of the lock 62 may be of such a kind that its key can only be removed with the lock in closed position. The operator of the machine would be compelled to close the frame lock, if he wants to take away his key at the end of the operation. If he then also dutifully locks the main lock 2 of the machine, then every part of the latter is arrested in a number of ways and accordingly any unauthorized use is also actually prevented, even if someone succeeded in making any of the latches inoperable through unauthorized interference. By means of the main lock 2 all of the keys and the organs actuated thereby are suitably arrested, the movement of the carriage is prevented and

the motor current cut out and furthermore the removal of the frame carrying the control members is made impossible in case the carriage does not stand in its right hand end position.

Even in the latter case any change of the adjustment of the control members is, however, only possible with the lock 62 unlocked. Also such change by the operator is therefore prevented when the key for the lock 62 is withheld from him. The same also applies to the total key 38 which has already been arrested by the closing of the main lock 2, but which key itself may also be locked by means of the lock 38. By means of the lock 38 the operator may also be prevented from taking totals, if only his superior will take the totals.

The releasing key 31 is not disturbed or moved by turning the shaft 18 upon closing the lock 2, because its pin 32 is not carried along with the longitudinal slot of the lever 30. When again the lock 2 is open the shaft 18 can be turned by tapping the releasing key 31, without moving the rod 21, for the reason that the pin 28 of the lever 18 can move freely in the long slot of the rod

(Fig. 4). The releasing key can therefore during the use of the machine be used without hindrance and without having any influence on the lock 2.

We claim as our invention:

5 1. A calculating or like machine comprising a machine frame, a carriage slidably arranged on the machine frame, a box-like frame, means for securing the box-like frame on the carriage, an operable member for locking the securing means, a latch for locking the said member in its locking position, a spring forcing the latch to its locking position, and an abutment provided on the machine frame for bringing the latch to an inoperative position in a certain column position of the carriage against the action of the spring.

10 2. A machine according to claim 1, in which a key-operable lock is provided for operating the locking member only when the latch has been brought to the inoperative position.
